SIGNORS TO REED ROLLER BIT COMPANY, OF HOUSTON, TEXAS, A CORPORATION
OF TEXAS.

DEEP-WELL-DRILLING APPARATUS.

Application filed December 6, 1926. Serial No. 152,947.

Our invention relates to the type of deep well drilling apparatus employing side roller cutters and cross rollers cutters intermediate the side cutters.

- 5 An objection exists to apparatus of this type in which the cross roller cutter is of cylindrical form, owing to the fact that all parts of said cross roller cutter do not have a true rolling action throughout its extent.
- 10 In hard formations the scraping action in a substantially cylindrical cutter has a tendency to wear off the teeth of the cutter sections.

- 15 A further objection to cross roller cutter bits is that in laminated formations, consisting of stratas of rock, and gumbo or sticky shale, the bit will become clogged, because no adequate means has been available to supply flushing fluid onto the bottom of the 20 hole beneath the cross roller cutters. Consequently the sticky material at the bottom of the hole is not carried away, but on the contrary, the cross roller cutters roll up balls of this sticky material, which collects between the cross roller cutter and the wall of the recess in which it works, causing the cross roller cutter to cease functioning properly, and this is particularly true of the central sections of said cross roller cutter.

- 25 One object of the present invention is to overcome the above objections.

- 30 Another object is to employ large diameter side cutters, together with large diameter outer sections of the cross roller cutters properly proportioned to the size of the side roller cutters, so that both cutters, i. e., the side roller cutters and said outer sections of the cross roller cutter, will have maximum cutting areas, and the said outer sections 35 will have a maximum tendency to revolve in soft, as well as in hard formations. To this end also we employ a loose sleeve or bushing for the cross roller cutter. The cutters will revolve on this bushing and the bushing in turn will revolve on the bearing pin, and the revolution of any one of the 40 cross roller cutter sections will assist the other or others to revolve, should they tend

to stick in soft formations, by transmitting motion through the revoluble bushing or 50 sleeve.

Other objects and features of the invention will appear from the following description.

Referring to the drawings:—

55 Figure 1 is a central vertical sectional view of a drilling head, the plane of section being through the side roller cutters.

Fig. 2 is a vertical central sectional view in a plane at right angles to Fig. 1 through 60 the cross roller cutter.

Fig. 3 is a bottom plan view of the apparatus.

The bit head 1 at its lower end has a recess, defined by inclined inner faces or walls 65 2, convergent upwardly and inwardly. From each of these inclined faces a stud or bearing 3 projects inwardly. This stud is formed integrally with the bit head and its axis is radial to the central vertical axis of 70 the apparatus and inclines downwardly and inwardly. On this integral projection is mounted a side roller cutter 4 of frusto-conical form, with a bushing 5 interposed between said roller cutter and the bearing 75 projection. This bushing takes the wear. It is held against rotation on the bearing projection by a dowel 6 passing through the base flange 7 of the bushing into a socket 8 of the bit head. Communicating with this 80 socket is the hole 9 leading to the outer side of the bit head through which any suitable implement may be inserted to knock out the dowel pin when the apparatus is to be dismantled.

85 This bushing has its base flange resting upon the inclined face 2 of the bit head, and it has a top or cover portion 5^a which encloses or overlies the end of the bearing projection 3.

90 The frusto-conical cutter is held on this bushing by a ring nut 10, screw threaded upon the slightly reduced inner end of the bushing, said ring nut reaching out over the roller cutter into a recess 11 thereof, so that 95 the roller cutter is held between this nut and

the base flange 7 of the bushing. Any suitable means may be employed for placing or removing the nut, such as a spanner wrench, the nut being formed to receive this. The bushing has a smooth interior and it can be placed in position on the projection or removed therefrom by simply slipping it onto or off from the projection. When in place, the bushing is held on the bearing projection 10 by a cross brace or bridge plate 12, which extends across the recess in the bottom of the head and bears at its ends, upon the cover portions 5^a of the bushings. The bridge piece is formed with upwardly and inwardly 15 inclined ends, so as to get a firm bearing contact with the bushings of considerable extent. The bridge piece is held in position by the bearing pin 13, which is supported at its ends in the depending sides 14, 14 of the head, being held at its ends in bearing openings of 20 the said sides by taper pins 15. A suitable bushing 16 may be interposed between the bearing pin and the bridge piece. This bridge piece, as shown in Fig. 2, is placed to one side of the vertical axial line of the apparatus, the left side of the bridge piece being in the plane of this axial line. This provides for spacing or locating roller cutters along this cross pin 13, which will cut 25 the formation throughout the area at the bottom of the hole. At the right of this bridge piece, as shown in Fig. 2, is mounted a cylindrical cutter roller 17 forming one section of the cross roller cutter, and to the right of 30 this is the frusto-conical roller cutter 17^a with a washer 18 interposed between it and the depending side 14 of the bit head and dowelled at 18^a to the latter. To the left of the bridge piece, as viewed in Fig. 2, 35 there are mounted on the cross pin two cylindrical roller cutters 17^b, 17^c, and a terminal frusto-conical cutter 17^d with a washer 18 interposed between the latter and the adjacent wall of the bit head 40 and dowelled at 18^a to the latter. The cylindrical rollers 17 and 17^b do not track, being located at different distances from the vertical axis of the apparatus, and hence the entire area at the bottom of the hole will be 45 acted on by the cutters. The two roller cutters 17, 17^a have interposed between them and the cross pin 13 a bushing 19 on which they are adapted to turn independently of each other, and this bushing is loose on the 50 cross pin so that it may turn thereon. Likewise the group of roller cutters 17^b, 17^c, 17^d are mounted to rotate upon a bushing 19^a common to them all and this bushing is mounted on the cross pin, so that it may rotate thereon. These bushings 19 and 19^a bear 55 on the washers 18 at their outer ends and upon the central bushing 16 at their inner ends.

By reason of this arrangement, if either 60 roller of either group tends to stick in soft

formation, while another roller of that group is rotating, the loose sleeve will be free to rotate by the frictional engagement of the rotating cutter therewith, and the rotation of the sleeve or bushing will tend to overcome 70 the sticking of the other roller and make it rotate with the sleeve and the active roller cutter. These bushings being free to rotate, divide the wear between themselves and the roller cutters and the bearing pin. They 75 also prevent any accidental squeezing together of the projection 14 from binding the cross roller cutters against rotation.

The side roller cutters 4, as shown in Fig. 1, cut the clearance around the bit head. 80 They are of maximum diameter to provide as large a cutting area as possible. The end cross roller cutters 17^a, 17^d are frusto-conical in form and they also are of large diameter and present a maximum cutting area for 85 working on the bottom of the hole. These frusto-conical cross roller sections or cutters cut an annular path within the diameter of the path cut by the side roller cutters and their larger or outer portions cut down to the 90 level of the bottom of the annular channel cut by the side roller cutters. It will be noted that the large diameter end of the frusto-conical rollers 17^a cut a path adjacent to the path cut by the smaller end of the 95 frusto-conical side cutters 4 and are at their outer portions of approximately the same diameter as the smaller diameter end of the said side cutters, thereby bearing the same ratio or relation to its distance from the vertical axis of the apparatus as the cutting area of the larger side roller cutters bear to their greater distance from the vertical axis 100 of the apparatus.

By this relation between the end sections 105 17^a, 17^d and the side roller cutters, substantially uniform wear takes place on these two sets of cutters and it is not necessary to pull the apparatus from the well because of one set of roller cutters wearing materially 110 faster than the others. Pulling the apparatus from the well to renew cutters involves the expenditure of much time and labor, which otherwise might be devoted to getting more depth of hole, so that with a cutter 115 organization in which all the cutter members wear substantially even and in proportion to the area they must cut, high efficiency is contributed to the operation of the apparatus.

It will be noted also that with the relative diameters of the roller cutter sections of the cross roller cutter organization, the bottom of the hole will have a frusto-conical 120 central portion or projection with the smaller end uppermost. The action of the outside frusto-conical cutters 17^a, 17^d on the sides of this projection left at the bottom of the hole, is, due to the wobble of the apparatus in the hole, to break down the mate- 125

rial of this projection by striking it a succession of blows distributed around its circumference. As is well known, the drill stem is somewhat flexible and the apparatus being at the lower end of a considerable length of stem, will have some lateral wobbling action and it is this movement which enables the frusto-conical cutters 17^a, 17^d to pound upon the central projection of the formation at the bottom of the hole to break it down without the frictional action usually attending the operation of the toothed cutter on the face of the rock formation.

For flushing the cutters the bit head is provided with the usual central channel for the flow of the flushing fluid, which is distributed to the various cutters by the ports 20. The bridge piece 12 has a channel 21 with a downwardly open mouth 22 for discharging the flushing fluid, received through the pipe 23, to the bottom of the hole, said discharge taking place below the cross roller cutter and washing away the cuttings at this point, while the ports 20 supply flushing fluid on top of the rotary cutters to keep them clear. This flushing system contributes largely to the successful operation of the apparatus in formations of a sticky nature, as well as in hard formations. Other water courses may be provided to play upon the bottom and outer edge of the hole, the water coming between the frusto-conical cross rollers to further flush the cuttings from the outer recess left by the side cutters.

The construction shown gives a liberal amount of clearance between the bit head and the bottom and side walls of the hole, this being greater than is usual.

The taper pins 15 for locking the cross pin 13 in place give advantageous results over the use of set-screws usually employed for this purpose. The latter become locked in the head either from rust or from the strains and stresses that the material of the head is subjected to, and it has been found necessary at times to have the set screws drilled out. The taper pins are not subject to these objections, as they can be knocked out when desired. They also serve a purpose in keeping the head from bending either inwardly or outwardly. The cross roller bearing pin 13 has an eccentric head 13^a seated in the downward projection of the bit head to hold said pin from turning.

We claim:

1. In combination in deep well drilling apparatus, a bit head having a recess in its lower face defined by upwardly and inwardly inclined walls with bearing projections on said walls inclining inwardly and downwardly towards the vertical axis of the apparatus, bushings on said projections, roller cutters on said bushings, means for retaining the roller cutter on the bushing, a

bridge piece extending across the recess of the head and bearing upon the bushings to hold them on the projections, a cross roller cutter within the recess, and a bearing pin for said cross roller cutter having its opposite ends seated in downwardly extending projections of the bit head, passing through the said bridge piece and holding the same in place, substantially as described. 70

2. In deep well drilling apparatus according to claim 1, in which the bushing has a flange at its outer side to bear on the wall of the recess of the head, and having a ring nut screwed upon its inner end to hold the side roller cutter between itself and said flange, substantially as described. 75

3. Deep well drilling apparatus according to claim 1 in which the bushing has a cover or top portion extending over the end of the projection and the bridge piece bears on said cover portion, substantially as described. 85

4. In combination in deep well drilling apparatus, a head having a recess in its lower face defined by upwardly and inwardly inclined walls, side roller cutters of frusto-conical form mounted on said inclined walls and of a diameter to cut clearance for the bit head, and a cross roller cutter in the recess, composed of cylindrical roller sections providing the central portion of said cross roller cutter and frusto-conical outer roller cutters of a diameter at their outer sides large than the diameter of the cylindrical sections, and of approximately 90 the same diameter as the smaller diameter ends of the frusto-conical side roller cutters, said outer sections of the cross roller cutter acting upon an annular path adjacent the inner edge of the path cut by the side roller cutters, all of said frusto-conical cutters having their smaller ends facing the axis of the drill head and having a cutting area proportioned to the paths they are to cut, substantially as described. 95 100

5. Deep well drilling apparatus according to claim 1 in which the bridge piece has a channel extending about the cross roller bearing pin and with a discharge mouth below said pin to discharge the flushing fluid at a point at the lower part of said cross roller cutter, said bridge being connected by a water course at its upper side with the water course through the drill head, substantially as described. 110 115

6. Deep well drilling apparatus according to claim 1 in which the bridge piece has a water course extending therethrough from top to bottom and discharging the flushing fluid directly against the bottom of the hole 125 at a point below the cross bearing pin, substantially as described.

7. In combination in deep well drilling apparatus, a head having a recess in its lower face with a bearing pin extending 130

across said recess with its ends seated in the walls of said recess, roller cutters arranged on said bearing pin, and a bushing interposed between said roller cutters and the pin and free to turn on the latter, said roller cutters being independently revoluble on said bushing whereby if one sticks, the other will tend to rotate it through the free bushing, substantially as described.

In testimony whereof, we affix our signatures.
